DESIGN FOR A SPOT WELDER

Chester A. Frick, Muncie, Ind.

Application July 17, 1935, Serial No. 57,682

Term of patent 14 years

To all whom it may concern:

Be it known that I, Chester A. Frick, a citizen of the United States, residing at Muncie, in the county of Delaware, and States of Indiana, have invented a new, original, and ornamental Design for Spot Welders, of which the following is a specification, reference being had to the accompanying drawing, forming part thereof.

The figure is a perspective view of a spot welder

embodying my design and showing one side of the welder, the opposite side being the same.

I claim:

The ornamental design for a spot welder, as shown and described.

In witness whereof I have hereunto set my hand at Muncie, Indiana, this 12th day of July, A. D. one thousand nine hundred and thirty-five.

CHESTER A. FRICK.
